UNITED STATES PATENT OFFICE.

FELICE SCOLARDI, OF PROVIDENCE, RHODE ISLAND.

CRADLE.

1,246,476.

Specification of Letters Patent. Patented Nov. 13, 1917.

Application filed May 17, 1917. Serial No. 169,159.

To all whom it may concern:

Be it known that I, FELICE SCOLARDI, a subject of the King of Italy, and resident of the city of Providence, in the county of 5 Providence and State of Rhode Island, have invented certain new and useful Improvements in Cradles, of which the following is a specification.

This invention relates to portable cradles, 10 and has for its object to provide such a cradle having end standards and a body member pivotally mounted to swing on said standards, and to provide base members for each standard having wheels operatively 15 mounted thereon.

A further object of this invention is to provide a hollow base member having a bottom plate with a plurality of apertures into which the wheels are inserted and having 20 an axle rod passing through said wheels and secured to this bottom plate, whereby the axle rod may be soldered or otherwise secured in position on the surface of this plate.

The invention further consists in making 25 the cradle very light by constructing both the standards and the frame of the body member of thin tubing, and to provide transverse tubes passing through the standards and the adjacent body rail, through which 30 a pivot bolt is passed, to support this body to swing on the standards.

With these and other objects in view, the invention consists of certain novel features of construction, as will be more fully 35 described, and particularly pointed out in the appended claim.

In the accompanying drawings:

Figure 1— is a perspective view showing the general construction of my improved 40 portable cradle.

Fig. 2— is an enlarged detail showing a portion of the tubular standard and body rail as having transverse tubes passed therethrough and through which transverse tubes 45 extends the pivot bolt on which the body member is pivotally supported.

Fig. 3— is a view partially in section showing the end of the tubular frame of the body member as connected to a hollow square 50 corner member.

Fig. 4— is an end view on line 4—4 of Fig. 5 through the hollow standard base.

Fig. 5— is a longitudinal section through the hollow standard base showing the general arrangement by which the rolls or 55 wheels are supported in said base.

Referring to the drawings, 10 designates the two opposite end standards which are supported from their respective base members 11, which standards are stayed from the base members by stay rods 12 and the two standards are connected together by cross bars 13. The upper end of each standard is drilled transversely to receive the small tube 14, see Fig. 2, which is soldered 60 or otherwise secured thereon and through which the pivot bolt 15 passes on which the body portion 16 of the cradle is pivotally supported.

The base 11 on each of these standards is 70 preferably constructed of sheet metal and is in hollow rectangular form. The upper plate 17 on each has its sides 18 bent downwardly as illustrated in Fig. 4 and its end 19 also bent downward as illustrated in Fig. 75 5; the corners on these sides and ends are soldered together.

A bottom plate 20 is provided for each of these base portions, which plate is provided with a plurality of openings as at 21 80 through which the rolls or wheels 22 project. These wheels are mounted on an axle 23 which extends longitudinally of this hollow base portion and is connected by solder or otherwise preferably to the inner face thereof, 85 whereby a single rod of wire serves as an axle upon which all of the wheels are mounted.

After the wheels have been positioned and the axle fixed to the face of this bottom 90 plate, the plate itself is connected to the base by solder or otherwise.

The body portion 16 of this cradle is also constructed of tubing. The ends of both the upper and lower frame rolls 24 and 25 95 are connected to the hollow square corner member 26 by solder or otherwise as illustrated in Fig. 3 and these upper and lower frames are connected by uprights 27 which tie these frames together in spaced-apart 100 relation.

The end rods 28 of the upper frame are bored transversely through their centers, as illustrated in Fig. 2, and a small tube 29 is passed through and secured in this opening 105 to provide an extended bearing for this pivot bolt 15 which serves to support the cradle body and permit the latter to freely swing thereon.

At the upper end of one of the standards 110 a socket member 30 is provided to receive the arm 31 which is for the purpose of sup-

porting a canopy, illustrated in dotted lines, over the cradle.

One of the features of my improved cradle, is that the same is constructed of 5 very thin tubing, and so is very light in weight and easily moved about; second, the base portion is provided with wheels rendering the cradle portable and its position easily shifted; third, by providing a hollow base 10 with a bottom plate having apertures therein through which the wheels extend; the side edges of these openings prevent lateral motion of the wheels on its axle and permit the single axle rod to extend through all of 15 the wheels, which is an extremely simple, effective and inexpensive construction for mounting these wheels upon this base.

The foregoing description is directed solely toward the construction illustrated, 20 but I desire it to be understood that I reserve

the privilege of resorting to all the mechanical changes to which the device is susceptible, the invention being defined and limited only by the terms of the appended claim.

I claim:

A portable cradle comprising tubular end standards, a body member constructed of tubing, said standards and the adjacent frame rails of said body member being provided with short transverse bearing tubes 30 passing through each, and a pivot bolt passing through said transverse tubes in said standards and rails to pivotally support the body on said standards. 35

In testimony whereof I affix my signature in presence of a witness.

FELICE SCOLARDI.

Witness:

HOWARD E. BARLOW.
